UNITED STATES PATENT OFFICE.

MAX G. SCHINKE, OF MILWAUKEE, WISCONSIN.

ROAD-ROLLER.

SPECIFICATION forming part of Letters Patent No. 660,203, dated October 23, 1900.

Application filed March 8, 1897. Serial No. 626,448. (No model.)

To all whom it may concern:

Be it known that I, MAX G. SCHINKE, of Milwaukee, in the county of Milwaukee and State of Wisconsin, have invented certain new and useful Improvements in Road-Rollers; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

The main object of my invention is to increase the efficiency of a roller used to level, smooth, spread, or compact material and to combine a tamping action with the usual smoothing action of the roller.

It consists of certain novel features in the construction and arrangement of component parts of the device, as hereinafter particularly described, and pointed out in the claims.

In the accompanying drawings like letters designate the same parts in the several figures. Figure 1 is a side elevation of a roller embodying my invention, certain parts being broken away and shown in section. Fig. 2 is a horizontal section of a part of the roller on the line 2 2, Fig. 1; and Fig. 3 is a vertical section on the line 3 3, Fig. 1.

For the purpose of illustration I have shown and will specifically describe my improvements as adapted and applied to a street or land roller, although they may be applied to rollers for other purposes where a tamping action is desirable in connection with the usual smoothing and compressing action of the roller. For certain uses, as for streetwork, the roller may be mounted in a suitable frame to be drawn or propelled over the surface to be operated upon, and for other uses, such as rolling out metals or kneading softer substances, the roller or rollers may be mounted in a stationary frame and the material to be operated upon fed thereto.

Referring to the drawings, A designates the roller-frame, which may be constructed of wood, as shown, or of any other suitable material and of any desired shape. In the present instance it is shown as quadrangular in

form. The roller may be made in one or more parts or sections, according to the use to which it is to be applied. In the present case it is shown as made of two parts or sections B B for facility in turning and operating it. Each 55 part or section is made hollow, with a central hub or bearing b, which is mounted to turn on an axle C, fastened at its ends to the sides of the frame A. The roller may be constructed of any suitable material, preferably of metal. 60 In the present case each part is shown as cast in one piece, with an internal rack, teeth, or projections b' arranged around its periphery concentrically with its hub b, which is formed integrally with one end, the other or outer 65 end being left open. The two parts are mounted end to end upon the axle C and are held close together by collars c c, placed on said axle next to the outer ends of hubs b. Each roller-section B is provided with a tamping or compacting weight D, which in the present case is of cylindrical form and mounted to turn on an axis parallel with the axis of the roller. Each of these rolling weights is adapted to traverse or bear against the interior of the rim of the roller-section B in which it is contained and is carried or guided in its proper relation thereto by a horizontally-disposed frame or support E, which is pivotally connected by a pin or bolt e at its front end 70 to a bracket a, depending from the side of frame A. At its opposite or rear end each support E is provided with a transverse rocking pin or shaft F, parallel with the pivot pin or bolt e. This shaft is provided at one end 75 with a depending dog f, adapted to engage with the inwardly-projecting teeth b' of the roller, and at the opposite or outer end it is formed or provided with an upwardly-projecting arm f', connected with the support E 80 by a spring f², which tends to turn and hold the dog f toward the periphery of the roller in the path of the teeth b'.

The rotary weight D, as shown, is formed or provided with an axled, bearing at its ends 95 in side pieces or brackets e' e', which project downwardly from the sides of the support E; but it may be made to turn upon instead of with said axle. Each weight D may be made of iron or other suitable material possessing 100

the requisite weight and provided on its periphery with a covering of elastic or non-resonant material. This covering may be constructed of wooden staves bolted to the flanged 5 ends of the weight, as shown. At each end of the roller or at the outer end of each part or section thereof a lever G is fulcrumed to the frame within convenient reach of the driver or operator. A sliding plate or bar 10 H, mounted on the frame A and held and guided thereon by suitable keepers, engages at one end with said lever and at the opposite or rear end with the arm f', as shown in Fig. 2. Each lever is provided with a spring-latch adapted to engage with the notches in 15 a sector g, attached to the frame. By means of this lever and its connections the dog f may be adjusted so as to engage with the teeth b' more or less, and thus vary the tamping movement and the force of the blows of weight D, or the dog f may be turned out of range with said teeth, so that the weight will 20 not be lifted from the rim of the roller, but will remain in contact therewith.

25 The operation of the roller will be apparent to those familiar with devices of this class. It will be seen that to the usual uniform smoothing action of the roller upon the material over which it passes a tamping action is added, by which energy or work is imparted 30 through the rim of the roller to the material acted upon. In consequence of this arrangement the machine has a much higher efficiency than ordinary rollers of like or greater 35 weight. The effect of the roller penetrates much deeper into the rolled material, and hard lumps or projections which would not ordinarily be affected by a simple roller of even greater weight than my machine will be 40 crushed and leveled by the tamping action of the weight. The force of the blows imparted by the tamping-weight is easily varied and 45 adjusted according to the condition of the material or surface operated upon, or the tamping action can be altogether discontinued whenever it is desirable to do so. Even without the tamping action the roller provided with a rotary weight adapted to traverse the interior of its rim opposite its bearing-surface facilitates the operation of the 50 roller and renders it more effective with a given weight for simple mechanical reasons which will be readily appreciated by those familiar with the art to which my invention 55 pertains.

I do not wish to be understood as limiting myself to the details of construction for the purpose herein shown and described, as they 60 may be variously modified, according to the use to which the device is to be applied, within the intended scope of my invention, and in this connection I desire to call attention to the fact that the tamping mechanism can be easily made and arranged to be operated 65 independently of the turning movement of

the roller—as, for instance, by steam; also, that the shape of the tamping-weight is not an essential feature of the machine, but may be made in the form of a hammer of any convenient or suitable shape.

I claim—

1. The combination with a hollow roller of a weight contained in said roller and arranged to strike against its rim and produce a tamping action upon the ground or surface over 70 which the roller passes, substantially as and for the purposes set forth.
2. The combination with a hollow roller, of a vertically-movable weight contained therein, and means of alternately lifting and dropping said weight against the working side of 80 said roller, substantially as and for the purposes set forth.
3. The combination with a hollow roller, of a tamping-weight contained therein and arranged to impart blows thereto, and means of regulating the force of said blows, substantially as and for the purposes set forth. 85
4. The combination with a hollow roller, of a rotary cylindrical weight contained therein, and having its axis substantially parallel therewith, and means of alternately lifting and dropping said weight, substantially as and for the purposes set forth. 90
5. The combination with a hollow roller, of a rolling weight guided therein with its axis parallel with the axis of the roller, means of alternately lifting and dropping said weight, and means of varying the distance that the weight is lifted, substantially as and for the 95 purposes set forth.
6. The combination of a hollow roller and a rotary cylindrical weight adapted to impart blows against the interior thereof and provided with a covering of elastic or non-resonant 100 material, substantially as and for the purposes set forth. 105
7. The combination with a suitable frame, of a hollow roller journaled therein, a support pivotally connected with said frame, a 110 weight attached to said support inside of the roller, and teeth or projections on the inside of said roller arranged to engage with said support and alternately lift and drop said weight when the roller is turned, substantially 115 as and for the purposes set forth.
8. The combination with a suitable frame, of a hollow roller journaled therein and provided inside with teeth or projections, a support pivotally connected with said frame, a 120 weight attached to said support opposite the working side of the roller, and a dog adjustably connected with said support so as to engage more or less with said teeth or projections, substantially as and for the purposes 125 set forth.
9. The combination with a suitable frame, of a hollow roller journaled therein and provided inside with a circular series of teeth or projections, a support pivotally connected 130

with said frame, a weight attached to said support within said roller, a dog pivotally connected with said support, and means of projecting said dog more or less into the path of said teeth, substantially as and for the purposes set forth.

5 In testimony that I claim the foregoing as

my own I affix my signature in presence of two witnesses.

MAX G. SCHINKE.
